UNITED STATES PATENT OFFICE.

GEORGE R. SHARP, OF LARNED, KANSAS.

ENVELOP FOR CIRCULAR-LETTERS.

1,108,257.

Specification of Letters Patent. Patented Aug. 25, 1914.

Application filed March 26, 1912. Serial No. 686,424.

To all whom it may concern:

Be it known that I, GEORGE R. SHARP, a citizen of the United States, residing at Larned, in the county of Pawnee and State 5 of Kansas, have invented certain new and useful Improvements in Envelops for Circular-Letters, of which the following is a specification, reference being had therein to the accompanying drawing.

10 This invention relates to envelopes and has special reference to an envelop adapted to be closed without the use of any adhesive material for effecting such closure.

15 The principal object of the invention is to improve and simplify the general construction of such envelopes.

With the above and other objects in view, the invention consists in general of certain 20 novel constructions, arrangements and combinations of parts, as will be hereinafter fully described, illustrated in the accompanying drawings, and specifically claimed.

25 In the accompanying drawings, like characters of reference indicate like parts in the several views, and: Figure 1 is a face view of an envelop constructed in accordance with this invention. Fig. 2 is a rear view thereof. Fig. 3 is a section on the line 3—3, Fig. 2.

30 In the form of envelop shown in Figs. 1, 2, and 3 an oblong blank is provided which is folded about the middle of its length to form a front 10 and a back 11. The edges of this blank are provided with lateral extensions which are folded over the back to provide side flaps 12. The end of the blank is also provided with a trapezoidal extension to form a closure flap 13. Extending from this trapezoidal closure flap is a tongue 14 and the flap is provided with a slit 15. This

tongue is preferably made from a stiffer material than the body of the envelop and is passed up through the slit 15, being glued to the flap 13 when made of different material, or formed integral therewith when made of the same material as the envelop. Furthermore, the tongue projects upward slightly above the mouth of the envelop when the latter is closed. In closing the envelop the flap 13 is tucked inside in the ordinary manner but when it is desired to open the envelop 45 the tongue 14 is grasped and drawn open when the closure 13 will readily slip out of the mouth of the envelop leaving the latter 50 free.

There has thus been provided a simple and efficient device of the kind described and for the purpose specified.

Having thus described the invention, what is claimed as new, is:—

An envelop comprising a body portion 60 having an open end, a closure flap extending from the open end of said body portion and provided with a transversely extending slit 65 and adapted to be placed within the open end of the body, and a tongue carried by and extending from the end of the closure flap in alinement with said slit whereby the tongue may be doubled back upon the flap with its free end passed through the slit and extending beyond the end of said body portion 70 when said closure flap is placed within the body portion.

In testimony whereof I hereunto affix my signature in presence of two witnesses.

GEORGE R. SHARP.
